UNITED STATES PATENT OFFICE.

CHARLES A. CHISHOLM, OF JENNINGSTON, WEST VIRGINIA, ASSIGNOR OF ONE-HALF
TO ANGUS CHISHOLM, OF JENNINGSTON, WEST VIRGINIA.

RIVET-SETTING IMPLEMENT.

Application filed March 10, 1927. Serial No. 174,339.

This invention relates to rivet setting implements and more particularly to a hand operated rivet setting device for setting split rivets.

As is well known to those familiar with the art, in setting a split rivet, an opening must be formed through which the rivet may be inserted, as it is impossible to drive this type of rivet through the material without so damaging the same that its effectiveness is destroyed. In order to provide an opening through which the split rivet may be inserted without the loss of considerable time, the opening must ordinarily be made of greater size than the rivet, thus partially destroying the effectiveness thereof. Accordingly, an important object of the invention is to provide a rivet setting device so constructed that the opening may be formed and the rivet inserted at a single operation.

A further object of the invention is to provide a device of this character including, as a portion of its necessary mechanism, an implement whereby the sections of the split rivet may be separated and prepared to receive the blow of a hammer or similar implement whereby the wings of the shank are clamped upon the material.

These and other objects I attain by the construction shown in the accompanying drawings, wherein for the purpose of illustration is shown a preferred embodiment of my invention and wherein:—

Figure 1 is a view partially in section showing a rivet inserting device constructed in accordance with my invention in use for inserting a split rivet through two pieces of material;

Figure 2 is a section on the line 2—2 of Figure 1;

Figure 3 is a section on the line 3—3 of Figure 1;

Figure 4 is a detail view partially in section showing the manner in which the end of the handle bar is used to spread the legs of the rivet.

Referring now more particularly to the drawings, the numeral 10 generally indicates a needle pointed at one end, as indicated at 11. Adjacent this pointed end, the needle is provided with an eye 12 elongated longitudinally of the needle. The opposite end of the needle is formed with a socket 13 adapted to receive the shank 14 of a split rivet. The walls of this socket are thin and at their

upper ends provide a seat upon which the under surface of the head 15 of the rivet may seat. In combination with a device of this character, I provide a handle bar 16 for the needle. This bar is pointed at one end, as indicated at 17, and shaped, so that it may enter the elongated eye 12 of the needle for a considerable distance. The opposite end 18 of the handle bar is acutely triangular in cross section and provides a wedge, the thinned edge 19 of which may enter the kerf 20 between the wings 21 of the rivet shank.

In the use of the shank, the split rivet, which is to be inserted, is placed with the shank in the socket 13 and the needle forced through the materials which are to be riveted to one another. At this time, if the resistance of the needle is excessive, a blow may be struck against the head of the rivet, which forms a head for the needle. When the needle has been inserted in the material so that the eye 12 appears at the opposite side thereof from the rivet head, the pointed end 17 of the cross bar is inserted in the eye and the bar employed as a handle, whereby the needle is drawn through the material until the head of the rivet is engaged against the face of the material and the needle is withdrawn from the shank of the rivet, leaving the same in position in the material.

It is pointed out that by the use of a needle of this character, the material is simply spread apart, so that it tends to close upon the shank of the rivet just as soon as the needle is withdrawn. This is due to the fact that the needle is tapered from end to end. After the needle has been withdrawn, the handle bar 16 may be removed and the edge 19 entered between the wings of the rivet and driven therebetween to spread these wings to a point where a blow of the hammer will clinch the same upon the material. It will, of course, be understood that a last or other suitable base will be placed against the head of the rivet during this operation to prevent the rivet from being backed through the material.

Since the construction hereinbefore set forth is capable of a certain range of change and modification without materially departing from the spirit of the invention, I do not limit myself to such specific structure except as hereinafter claimed.

I claim:—

Means for inserting split rivets in mate-

rial comprising a member tapered from end to end, one end of the member being pointed, the opposite end of the member having a socket adapted to receive the shank of the split rivet which is to be inserted, said member having adjacent its pointed end an eye elongated longitudinally thereof, and a handle bar having a pointed end adapted for insertion in said eye to thereby provide a grip

whereby the member may be drawn through the material, and on its other end a wedge-shaped structure the smaller end of which is adapted to enter the split of the rivet to thereby force the wings thereof apart.

In testimony whereof I hereunto affix my **15** signature.

CHARLES A. CHISHOLM.
